UNITED STATES PATENT OFFICE.

J. A. AYRES, OF HARTFORD, CONNECTICUT.

IMPROVEMENT IN SCREWS.

Specification forming part of Letters Patent No. 38,141, dated April 14, 1863.

To all whom it may concern:

Be it known that I, J. A. AYRES, of Hartford, in the county of Hartford and State of Connecticut, have invented a new and useful Improvement in Screws; and I do hereby declare that the following is a full, clear, and exact description of the same, reference being had to the accompanying drawings, forming a part of this specification, in which—

Figure 1 represents a side elevation of my invention. Fig. 2 is a longitudinal central section of the same.

Similar letters of reference in both views indicate corresponding parts.

This invention consists in the arrangement of a dovetailed slot in the head of a screw in such a manner that the edges of said slot afford a good and firm hold to the screw-driver, and that said slot is not liable to wear out and let the screw-driver slip.

To enable those skilled in the art to make and use my invention, I will proceed to describe it with reference to the drawings.

The slots in ordinary screws are made with parallel sides, and if the screw-driver is inserted the edges of said slot are soon rounded off and the screw-driver is liable to slip, and after a screw with such a slot has been repeatedly screwed in and out the slot is, in many cases, so spoiled that it does not afford sufficient hold to the screw-driver to work the screw, and consequently the screw is ren-

dered useless. It is, however, more particularly the annoyance occasioned by the slipping of the screw-driver in the slots of ordinary screws which I have endeavored to obviate by my invention.

The sides of the slot *a* of my screw *A* are inclined inwardly, so that a cross-section or end view of the slot presents the shape of a dovetail, as clearly shown in the drawings. This slot may be cut by means of two saws set at a slight angle, or by any other suitable device, and when properly cut it presents two sharp edges, *b*, which afford a good hold to the screw-driver, and which are not liable to wear away so as to render the screw useless.

It is obvious that this improvement is applicable to screws of any size and shape, the heads of which are provided with a slot, and wherever applied it will be found that the annoyance occasioned by the slipping of the screw-driver in the slots of ordinary screws is completely obviated by this apparently simple invention.

Having thus fully described my invention, what I claim as new, and desire to secure by Letters Patent, is—

A screw, *A*, with a dovetailed slot, *a*, as and for the purpose set forth.

J. A. AYRES.
